UNITED STATES PATENT OFFICE

JOHN B. DOUGAN, OF CANONSBURG, PENNSYLVANIA, ASSIGNOR TO CONTINENTAL CAN COMPANY, INC., OF NEW YORK, N. Y., A CORPORATION OF NEW YORK

TIN MACHINE

Application filed November 12, 1928; Serial No. 318,870.

The invention relates to new and useful improvements in tin machines for coating metal plates with tin, and more particularly to the driving mechanism for the feed rolls 5 of the tin machine.

It is customary to provide the feed rolls of a tin machine with intermeshing gears for positively actuating the feed rolls. The gears are all located within the tin pot and it is well known that the gear running in the molten tin will take up tin onto the gear with which it meshes, and this carries the molten tin onto the driving gear which actuates the gears associated with the feed rolls. The 10 tin sets on the driving gear and it is often necessary to remove the gear for the purpose of cutting away the tin.

An object of the present invention is to provide a driving mechanism for the feed rolls 20 which feeds the sheets through the tin machine with means for preventing the molten tin carried up by the gears associated with the feed rolls from accumulating and setting on the actuating means for said gears.

25 A further object of the invention is to provide a driving mechanism of the above type wherein the gears associated with the feed rolls are driven by a driving gear spaced from and connected to the gear associated with the uppermost feed rolls so that the molten tin carried up by the gears associated with the feed rolls is prevented from accumulating and setting on the driving gear.

30 A still further object of the invention is to provide a driving mechanism of the above type with means located in the space between the driving gear and the gear associated with the uppermost rolls on which the molten tin carried up by the gears accumulates and is caused by gravity to drop back into the tin pot.

35 These and other objects will in part be obvious and will in part be hereinafter more fully disclosed.

In the drawings which show by way of illustration one embodiment of the invention:—

Fig. 1 is a vertical sectional view on the 40 line 1—1 of Fig. 2 through a portion of a tin

machine having the improved driving mechanism for the feed rolls embodied therein.

Fig. 2 is a view showing more or less diagrammatically the feed rolls, the housing for supporting the same, the actuating gears associated with the feed rolls, and the driving gear therefor.

Fig. 3 is an enlarged view in vertical section of the gear associated with the topmost feed rolls and the driving gear spaced from 60 and connected thereto.

Fig. 4 is an enlarged detail in section through a portion of the gears shown in Fig. 3.

The invention is directed to a tin machine 65 and more particularly to the driving mechanism for the feed rolls. The tin machine is of the usual construction and includes a tin pot in which is maintained a bath of molten tin on the surface of which is an oil bath. 70 Extending into the oil bath and the molten tin is a housing carrying pairs of feed rolls which receive and feed the sheets in succession through the tin machine. These feed rolls are positively actuated by a train of 75 gears which are intermeshed and the lowermost gear of the train extends down into the molten tin. The uppermost gear of the train extends partway into the oil bath. This train of gears associated with the feed rolls 80 is driven by a gear which is spaced from but connected to the gear associated with the topmost rolls. Therefore, this driving gear extends into the oil bath. Between the gears there is an annular space and at the bottom of 85 this annular space there is a V-shaped rib. An operating gear meshes with this driving gear. Any tin carried up by the intermeshing train of gears onto the gear associated with the upper feed rolls and running off into the recess between the driven gear and the driving gear will accumulate on said V-shaped rib, and as this runs in the hot oil it 90 will drop therefrom back into the tin bath.

Referring more in detail to the drawings, 95 the tin pot is indicated at 1 and is of the usual construction. The metal line is indicated at *a—a* and the molten metal is located beneath this line. The oil line is indicated at *b—b* and the oil bath is located beneath this line 100.

and above the metal line. The depth of the metal bath and of the oil bath is immaterial to the present invention. Located within the tin pot is a housing 2 carrying pairs of feed rolls; the lowermost pair indicated at 3, 3 in Fig. 2, the intermediate pair at 4, 4, and the upper pair at 5, 5. These feed rolls operate to receive the sheets in succession and feed the same through the tin machine. The lowermost pair of feed rolls are driven by means of a driving gear 6 which is mounted on a shaft carrying one of the rolls 3. At the opposite end of this pair of feed rolls there are intermeshing gears so that both feed rolls 15 are positively driven. The intermediate feed rolls 4, 4 are driven by a gear 7 which meshes with the gear 6. There are also intermeshing gears at the opposite ends of these rolls 4, 4 so that both feed rolls are positively driven. The upper feed rolls 5, 5 are driven by a gear 8 which meshes with the gear 7. At the opposite ends of the rolls 5, 5 there are intermeshing gears so that both of these rolls are positively driven. The gears 6, 7, and 8 25 make up a train of gears which are the driven gears for actuating the feed rolls. The lowermost gear 6 extends into the oil bath and the uppermost gear 8 extends above the oil bath.

Associated with the uppermost gear 8 is a 30 driving gear 9. As shown in the drawings, it is formed integral therewith and the two gears are mounted on the shaft carrying one of the feed rolls 5. The driving gear 9 is spaced from the driven gear 8. The annular 35 space between the gears is indicated at 10 in the drawings. Located in this annular space is an annular rib 11 which, as shown in the drawings, is V-shaped in cross section.

The driving gear 9 is operated by a gear 10 12 carried by a shaft 13 mounted in a suitable bracket 14 carried by the frame of the tin machine. This shaft 13 may be actuated in any suitable way. The gear 12 meshing with the gear 9 drives said gear. This becomes the 15 driving gear of the train of mechanism for actuating the feed rolls.

In the operation of the machine, the molten tin is carried up by the teeth of the gear 6 onto the gear 7 and will be carried up by the teeth 50 of the gear 7 onto the gear 8. The gear 8 runs in part in the bath of hot oil. The tin on the gear 8 will be maintained in a molten condition. Any tin accumulating on the gear 8 and flowing over into the recess 10 will follow 55 the line of arrows in Fig. 4. Thus it is that the molten tin will flow out on the V-shaped rib, and as this rib passes beneath the surface of the hot oil the molten tin will drop from the vertex of the V-shaped rib back into the 60 hot bath and through the oil back into the tin bath. This recess and V-shaped rib prevent any possible passing of the molten tin onto the teeth of the driving gear 9, and of course, prevent thereby any molten tin being carried 65 up onto and setting on the driving gear 12.

It will be apparent, therefore, by the improvements described that means has been provided for preventing tin from being carried up from the tin bath onto the driving gear above the oil bath and setting thereon, 70 requiring a taking out of the gear and the cutting of the set tin from the gear. The driving gear above the oil bath is freed from the tin carried up by the train of gears on the feed rolls, and therefore, the tin machine may 75 be operated continuously without shutting down to change the driving gears for the feed rolls.

It will be obvious that other ways may be provided for preventing the tin from being 80 carried up by the driving gears from the tin bath onto the driving gear above the oil bath without departing from the spirit of the invention as set forth in the appended claims.

Having thus described my invention what 85 I claim as new and desire to secure by Letters Patent is:—

1. In a tin machine the combination of feed rolls for feeding the sheets, intermeshing gears for positively rotating said rolls, means for actuating said gears, and means for collecting the molten tin carried up by the driving gears on said rolls and for directing the same away from the actuating means for said gears.

2. In a tin machine the combination of feed rolls for feeding the sheets, intermeshing gears for positively rotating said rolls, an independent driving gear connected to said feed roll gears for actuating the same, and means for collecting the molten tin carried up by the driving gears on said rolls and for directing the same away from the actuating means for said gears.

3. In a tin machine the combination of feed rolls for feeding the sheets, a train of intermeshing driven gears for positively rotating said rolls, a driving gear spaced from and connected to the driven gear associated with the uppermost feed rolls, means for actuating said driving gear, and means located in the space between said gears for preventing molten tin carried up by the train of gears associated with the feed rolls from accumulating and setting on the driving gears for said train.

4. In a tin machine the combination of feed rolls for feeding the sheets, a train of intermeshing driven gears for positively rotating said rolls, a driving gear spaced from and connected to the driven gear associated with the uppermost feed rolls, means for actuating said driving gear, an outwardly projecting V-shaped annular rib located in the space between said gears on which the molten tin carried up by the train of gears accumulates and from which it passes back into the tin bath.

5. In a tin machine the combination of a tin pot adapted to contain a tin bath having an oil bath resting on the tin bath, feed rolls 130

for feeding the sheets, the lowermost rolls being disposed adjacent the tin bath and the uppermost rolls being disposed so as to be partially immersed in the oil bath, a train of gears associated with the feed rolls for rotating the same, a driving gear spaced from and connected to the driven gear of the uppermost feed rolls, a V-shaped outwardly projecting annular rib located centrally of said space and partially immersed in the oil bath, a driving gear meshing with said spaced driving gear for actuating the same and the train of driven gears connected to said rolls, said V-shaped rib operating to receive the molten tin carried up by the train of driven gears for directing said molten tin away from the driving gear and back into the tin bath.

In testimony whereof, I affix my signature.
JOHN R. DOUGAN.
